DESIGN FOR AN AUTOMOBILE

Robert E. Billings, City Island, N. Y., assignor to Richfield Oil Corporation of New York, New York County, N. Y.

Application May 29, 1934, Serial No. 51,955

Term of patent 7 years

To all whom it may concern:

Be it known that I, ROBERT E. BILLINGS, a citizen of the United States, residing at No. 477 King Avenue, City Island, county of Bronx, State of New York, have invented a new, original, and ornamental Design for an Automobile, of which the following is a specification, reference being had to the accompanying drawing, forming part thereof.

I claim:

The ornamental design for an automobile, as shown.

Dated, April 4th, 1934.

ROBERT E. BILLINGS.
